UNITED STATES PATENT OFFICE

2,497,580

ADJUSTABLE PHOTOGRAPHER'S POSING CHAIR

Claude M. Briggs, Elk City, Okla., assignor of one-third to John Overton Shaw, Elk City, Okla.

Application March 24, 1945, Serial No. 584,625

1 Claim. (Cl. 155—94)

1

This invention relates to a photographer's posing chair, and one of the objects of the invention is to provide means for quickly adjusting the seat to various elevations, which will be positive in its operation, and not interfere with the free turning of the seat.

Another object of the invention is to provide a head or arm rest supporting bar, arranged to slide in vertical guides, and a simple quick operating means for locking the bar in any position it is adjusted to.

A still further object of the invention is to provide a posing chair for photographers, which can be also adapted to accommodate persons of different sizes, by simple mechanical operations and the use of friction clutches for holding the seat post and the head rest bar in adjusted positions.

With the above and other objects in view, the invention relates to certain new and useful constructions, combinations and arrangements of parts, clearly illustrated in the accompanying drawings, and fully described in the following specification. In the drawings:

Fig. 1 is a side elevation.

Fig. 2 is a side elevation of the seat.

Fig. 3 is a cross sectional view, taken on line 3—3 of Fig. 2, looking in the direction of the arrows.

Fig. 4 is a bottom plan view of the seat.

Fig. 5 is a bottom plan view showing the clutch for holding the seat post in vertically adjusted position.

Fig. 6 is a side elevation thereof, showing the seat post broken away for convenience of illustration.

Fig. 7 is a detail side elevation, showing the clutch and mounting for adjustably supporting the back or head rest bar.

Fig. 8 is a detail bottom plan view thereof.

Referring to the accompanying drawings, which illustrate the practical application of the invention, 5 designates a series of chair legs, which are connected at their upper ends to the top 6, and by the brace board 7 intermediate of their upper and lower ends. On the top 6 a metal bearing plate 8 is secured.

A round or cylindrical seat post 9 is slidable through the top 6 and through the brace board 7. This seat post is vertically adjusted by means of the clutch plate 10, which is hingedly connected at 11 to the leaf or plate 12, attached directly to the underside of the brace board 7, by the screws 13. The hole 10a of the clutch plate 10 is somewhat larger than the post, so

5 that the clutch plate may be tilted downwardly under the brace board 7, and in order to hold the clutch plate 10 in clutching position, a spreader plate or member 14 is pivoted at 14a to the underside of the brace board and is adapted to be swung under the brace board to maintain the clutch plate or leaf 10 in tilted relation to the brace board.

10 On the upper end of the seat post 9 a roller bearing head 15 is arranged, and on this head the customer seat top 16 is mounted, so that it turns with a minimum of friction. A rubber cushion or buffer ring 9a is placed around the seat post 9 below the roller bearing head 15, so as 15 to cushion the seat when it is dropped to its lowest position against the lower chair top 6. Another rubber ring or buffer 9b is secured to the lower end of the seat post, to cushion the post when it is raised to its highest position.

20 When the clutch plate 10 is in inclined or tilted relation, it has a clutching action on the round seat post, as the lowermost and uppermost edges of the post opening or hole 10a are forced into pressure engagement with the sides 25 of the post, due to the tilting action of the plate 10 against the post, which is held to its normal vertical plane by the bearings of the top 6 and the brace board. By forcing the outer end of the plate 10 upwardly, the seat post may be freely 30 shifted upwardly or downwardly, to change the elevation of the seat top 16.

The seat top 16 is equipped with parallel guide bars 17 and 18, and on the bar 17 a metal strip 17a is secured, so that the inner edges of this 35 strip project inwardly of the inner side of the bar, and on the bar 18 the metal strip 18a is secured, and its inner edge projects inwardly of the inner edge of the bar 18. These bars and strips are arranged in spaced parallel relation to each other. These guide bars and strips are 40 located outwardly of the center of the seat top 16, and spaced apart sufficiently to receive the horizontal bar 19, which together with the vertical bar 20, and the diagonal brace 21, forms a horizontal sliding frame for the vertically adjustable head or head rest bar 22. The ends of the vertical frame bar 20 are provided with metal plates 23 and 24, which are secured thereto by screws 45 25, and these plates engage the sides of the bar 22.

An angle bar 26 is secured to the horizontal bar 19, and on the outer ends of the angle bar 26 the inner ends of the screw threaded rods 27 and 28 are coupled by the nuts 29. On the outer ends of the rods 27 and 28 the clutch bar 30 is rigidly

connected. The rods 27 and 28 are normally tilted so that the frictional pressure of the head rest bar 22 against the inner side of the clutch bar 30 will cause the bar 30 to swing inwardly, thereby increasing the pressure developed between the meeting surfaces of the bar 22 and the bar 20, and preventing downward movement of the head rest bar 22.

The bar 22 may be equipped with a rest 31 which may be adjusted to support the head, arm or back of the user. To prevent the horizontal bar 19 from becoming detached from the seat top 16, a stop pin 33 is secured to the metal strip 17a, and is engaged by the cross angle bar 26, as indicated in Fig. 1, when the angle bar reaches the limit of its horizontal travel. The normal friction between the sliding bar 19 and the bars or guides 17 and 18 and their plates is sufficient to prevent accidental sliding of the rest on the chair top 16.

By lifting the clutch bar 30 the sliding rest supporting bar 22 may be freely adjusted upwardly or downwardly. When the bar 30 is allowed to return to its normal inclined position, the friction of the sliding bar 22 on the bar 30 will increase the pressure of the clutch bar.

The adjustment of the chair post and its top seat is made without the delay usually required for the operation of a jack screw, and the same is true of the vertical adjustment of the rest bar.

It is understood that various changes in the details of construction, their arrangement and combination, may be resorted to, within the scope of the invention, as defined by the claim hereof.

Having described my invention, I claim as new:

A posing chair, comprising legs, a top supported

at the upper ends of the legs, a brace board intermediate the upper and lower ends of the legs, a seat supporting post slideable through the brace board and the top, a clutch plate hinged to the underside of the brace board and provided with a hole through which the seat post extends, said hole being larger than the seat post to permit of tilting of the plate away from the brace board, and a member pivoted to the brace board and adapted to swing between the plate and brace board to maintain the plate in clutching engagement with the post, whereby the post will be effectively prevented from longitudinal sliding movement, and a seat mounted on the upper end of the seat post.

CLAUDE M. BRIGGS.
